DESIGN FOR A PLASTIC UTILITY TABLE

Edmund D. Kissling, New York, N. Y.

Application December 10, 1945, Serial No. 124,580

Term of patent 14 years

(Cl. D33—14)

To all whom it may concern:

Be it known that I, Edmund D. Kissling, a citizen of the United States of America, residing at New York, in the county of New York and State of New York, have invented a new, original, and ornamental Design for a Plastic Utility Table, of which the following is a specification, reference being made to the accompanying drawing, forming a part thereof, in which

Fig. 1 is a front elevational view of a plastic utility table, showing my new design, and

Fig. 2 is an elevational view of my same design shown in Fig. 1, with the table turned at about 45 degrees.

I claim:

The ornamental design for a plastic utility table, as shown.

EDMUND D. KISSLING.
